VALVE RECONDITIONING CHUCK

Francis G. Livingston and Oren B. Harmes,
Algona, Iowa, assignors to Livingston Tool Co.,
Algona, Iowa, a partnership composed of
Charles L. Livingston and Francis G. Livingston

Application March 27, 1950, Serial No. 152,040

4 Claims. (Cl. 51—185)

1

This invention relates to valve reconditioning tools.

An object of our invention is to provide a tool for reconditioning valves which will provide the valves with a new valve face having the exact inclination desired for co-operation with a valve seat of given inclination.

Another object is to provide a valve reconditioning tool capable of utilizing a sheet abrasive and having provision therein for quick, simple and easy changing of such sheets.

Another object is to provide a tool for reconditioning valves which will form a new valve face of the exact inclination desired with a minimum of loss of the body material of the valve.

A further object is to provide a novel and improved valve reconditioning tool of cheap and simple construction capable of quick and easy operation by unskilled labor.

These and other objects and advantages of our invention will more fully appear from the following description made in connection with the accompanying drawings, wherein like reference characters refer to similar parts throughout the several views and, in which:

Fig. 1 is a side elevational view of the tool being used in conjunction with a vise;

Fig. 2 is a vertical sectional view of one embodiment of our invention;

Fig. 3 is a top plan view of the tool with a portion broken away;

Fig. 4 is a side elevational view of the adapter;

Fig. 5 is a bottom elevational view of the adapter;

Fig. 6 is a sectional view along line 6—6 of Fig. 2;

Fig. 7 is a bottom elevational view of a valve being reconditioned, showing the bore of the chuck in broken lines;

Fig. 8 is a plan view of an abrasive sheet formed for use in conjunction with our tool;

Fig. 9 is a side elevational view of a shank adapted for use in conjunction with our tool and a power-driven drill.

One embodiment of our invention, as shown in Figs. 1—9, includes a generally cylindrical body commonly known as a chuck 10 which is provided with a pair of flattened sides 11 adjacent its lower end and a threaded external portion 12 adjacent its upper end. The chuck 10 is also provided with an annularly shaped recess 13. Extending between the upper end of the annular recess 13 and the upper edge of the chuck 10 is a generally frusto-conically shaped reference surface 14 which is annularly arranged about the recess and extends outwardly and upwardly toward said upper edge. This reference surface 14 is formed at any desired angle relative to the bore of the recess 13.

A retaining nut 15 is provided with internal threads 16 adapted to co-operate with the threaded external portion 12 of the chuck 10

so as to secure the retaining nut 15 to the chuck. The retaining nut 15 is provided with an overhanging lip 15a which extends downwardly and annularly in overlying relation to the upper portion of the reference surface 14.

The bore of the recess 13 is of such dimensions as to accommodate the butterfly structure 17 commonly found on the lower portion of the valve indicated generally as 18. The bevelled face 19 of the valve 18 which is to be reconditioned is best shown in Fig. 2. Many valves, and especially those found in homogenizers, have an upstanding generally cylindrical portion 20 adjacent their upper end. This cylindrical portion 20 as shown in Fig. 6 is normally provided with a pair of flattened sides 21. To enable the operator to cause the valve 18 to turn relative to the reference surface 14 we have provided an adapter 22 which, as best shown in Figs. 5 and 6, has its lower portion 23 formed to accommodate in a snug fit the upstanding portion 20 and has its upper portion formed to receive the hexagonally shaped lower end of a torque-applying shank 24 of a speed wrench 25.

Fig. 8 shows an abrasive sheet 26 formed of such shape and dimensions so as to smoothly cover the reference surface 14 of a given inclination when annularly arranged relative thereto. These abrasive sheets 26, of course, must be formed of a different size and shape for each reference surface having a different angle of inclination. The pattern for such abrasive sheets 26 is attained by cutting a cone of the desired angularity and flattening the same upon a flat surface.

Fig. 9 shows a shank 27 which is adapted on its upper end 28 to be accommodated by a power-driven drill (not shown) and at its lower end 29 to receive thereon the adapter 22.

In operation, the retaining nut 15 is first loosened with the fingers or removed entirely and an abrasive sheet 26 of the necessary shape and dimensions is annularly arranged and applied to the reference surface 14 in smooth relation thereto. This is best accomplished by causing the ends of the abrasive sheet 26 to be brought together in registering relation. If the proper abrasive sheet 26 is used with respect to the angle of inclination of the chuck 10 which is being used, the abrasive sheet will exactly fit the reference surface 14 of the chuck 10 without overlap. It is a simple operation to tighten the retaining nut 15 by turning it relative to the chuck 10 whereupon the threads 16 will engage the threaded portion 12 of the chuck 10 and cause the retaining nut 15 to move downwardly relative to the chuck 10 until the lip 15a engages the upper end of the abrasive sheet 26. When the retaining nut 15 has been tightened snugly, this lip 15a will clamp the abrasive sheet 26 securely against the reference surface 14 to preclude it from turning relative thereto. This operation results in pre-

senting to a valve 18, which is in need of reconditioning, an abrasive reference surface having the desired angle of inclination.

The valve 18 is then placed upon the chuck 10 so that the butterfly structure 17 normally found along its lower portion will fit within the walls of the bore of the recess 13 and register therewith. The recess 13 will thus provide centering and a bearing for the valve 12 when it is turned relative to the chuck 10 and the reference surface 14 with its abrasive sheet 26. To facilitate the turning of the valve the adapter 22 is applied to the upstanding portion 20 of the valve 18 as is best shown in Figs. 1 and 2 and the speed wrench 25 is secured to the upper portion of the adapter 22. By causing the speed wrench to turn, the operator will cause the valve 18 to turn relative to the abrasive surface provided if the chuck 10 is held immovable as in a vise, as shown in Fig. 1. By repeated turning of the valve 18 in this manner, a new valve face 19 having the exact desired inclination will be formed. If the old valve face is badly worn, the valve may be turned rapidly by utilizing the adapter 22 in conjunction with the shank 27 and a power-driven drill (not shown).

In the event that a new abrasive sheet 26 is needed it can be readily seen that it is a quick and easy matter to loosen the retaining nut 15, remove the old and worn abrasive sheet and insert a new abrasive sheet to replace it. By merely tightening the retaining nut 15 the tool is again immediately ready for reconditioning operation.

It should be noted that our invention provides a tool for reconditioning valves which will form a new valve face having the exact inclination desired for co-operation with a valve seat of given inclination. This is accomplished by simply selecting a chuck 10 which has a reference surface 14 of the desired inclination and performing the operation described above.

It should also be noted that our tool is capable of utilizing a sheet abrasive in contrast to the conventional means of grinding valves which utilizeslapping compound. Our tool eliminates the muss and other disadvantages involved in using a lapping compound and provides a quick, simple and easy method of changing the abrasive sheets which are used instead.

One of the other advantages of our tool is that a new valve face can be formed on a worn valve which will have the exact desired inclination without employing specially designed cutters. Such cutters when used, although they provide a new valve face of the desired inclination, necessitate the removal and loss of a substantial portion of the body of the valve itself. Our tool provides a new valve face of the exact inclination desired with a very minimum of loss of the body material of the valve, since all that is required is that the operator cease to revolve the valve 18 as soon as the new valve face has been formed.

Another advantage of our tool is that it is of cheap and simple construction and can be used in a quick and easy manner by even the most unskilled laborer. Because of the centering which is provided for the valve 18 by the bore of the recess 13 it is impossible for the operator to form a valve seat which does not conform to the required specifications.

It will, of course, be understood that various changes may be made in the form, details, arrangement and proportions of the various parts without departing from the scope of our invention.

What we claim is:

1. A valve reconditioning tool comprising a body having an annular recess formed therein of dimensions to snugly receive the lower portion of the valve to be reconditioned in order to provide centering and a bearing for said valve, said body having a frusto-conical supporting surface annularly arranged around said recess and adjacent the outer end thereof for smoothly receiving an abrasive sheet thereon, and clamping means associated with said body for engaging the upper end of said abrasive sheet to smoothly clamp said sheet against said supporting surface.
- 15 2. A valve reconditioning tool comprising a body having an annular recess formed therein of dimensions to snugly receive the lower portion of the valve to be reconditioned in order to provide centering and a bearing for said valve, said body having a supporting surface annularly arranged around said recess and adjacent the outer end thereof for smoothly receiving an abrasive sheet thereon, said body having an externally threaded portion adjacent said supporting surface, and an internally threaded retaining-nut 20 25 adapted to cooperate with said threaded portion of said body to secure an abrasive sheet in smooth overlying relation with said supporting surface and fixed relative thereto.
- 30 3. A valve reconditioning tool comprising a body having an annular recess formed therein of dimensions to snugly receive the lower portion of the valve to be reconditioned to provide centering and a bearing for said valve, said body having a supporting surface annularly arranged 35 around said recess and adjacent the outer end thereof for smoothly receiving an abrasive sheet thereon, and clamping means associated with said body for engaging the upper edge of the abrasive sheet to smoothly clamp the same 40 against said supporting surface, said clamping means including a lip member overhanging the upper edge of said abrasive sheet to effectively clamp the abrasive sheet smoothly against said supporting surface.
- 45 4. A valve reconditioning tool comprising a body having an annular recess formed therein of dimensions to snugly receive the lower portion of the valve to be reconditioned to provide centering and a bearing for said valve, said body having a frusto-conical reference surface annularly arranged around said recess and adjacent the outer end thereof, a flat flexible abrasive sheet formed to a shape and to dimensions to overlie said frusto-conical reference surface when annularly 50 55 arranged relative thereto, and clamping means associated with said body for engaging the upper end of said abrasive sheet to smoothly clamp said sheet against said reference surface.
